United States Patent Office

Des. 194,159
Patented Nov. 27, 1962

194,159

ESCUTCHEON

Fred J. Russell, Los Angeles, and George B. Solovieff,
South Gate, Calif.; said Solovieff assignor to said
Russell

Filed Nov. 13, 1961, Ser. No. 67,477

Term of patent 14 years

(Cl. D50—6)

FIGURE 1 is a front elevational view of an escutcheon showing our design.

FIGURE 2 is a vertical sectional view on the line 2—2 of FIGURE 1.

FIGURE 3 is a vertical sectional view on the line 3—3 of FIGURE 1.

FIGURE 4 is a front perspective view of the design on a reduced scale. The portions shown in broken lines are for illustration only.

We claim:

The ornamental design for an escutcheon, as shown and described.
